UNITED STATES PATENT OFFICE.

CLARENCE W. WHEELER, OF CHICAGO, ILLINOIS, ASSIGNOR, BY MESNE ASSIGNMENTS, TO OTIS ELEVATOR COMPANY, OF JERSEY CITY, NEW JERSEY, A CORPORATION OF NEW JERSEY.

ELECTRIC-ELEVATOR BRAKE.

1,178,115.

Specification of Letters Patent.

Patented Apr. 4, 1916.

Application filed October 1, 1906. Serial No. 336,901.

To all whom it may concern:

Be it known that I, CLARENCE W. WHEELER, a citizen of the United States, and a resident of Chicago, in the county of Cook and State of Illinois, have invented a certain new, useful, and Improved Electric-Elevator Brake, of which the following is a full, clear, and exact description, such as will enable others skilled in the art to which it appertains to 10 make and use the same.

My invention relates to electric elevators, and particularly to automatic brakes for electric elevators.

Through inadvertence of the operator or 15 faulty working of the mechanism it sometimes occurs that an elevator car is carried beyond its proper stopping point at the top or bottom of the shaft, with consequent damage to the building, or to the hoisting 20 mechanism and not infrequently inflicting serious injury upon the occupants of the car.

The object of my invention is to provide improved emergency brake operating mechanism.

More particularly it is the object of my invention to provide automatic means for effecting the application of a brake at pre-determined limits of travel of elevator hoisting mechanism and combining therewith an 25 auxiliary device to operate emergency brake-applying mechanism beyond such limits and having a single electro-magnet which will be capable of releasing the brake both at the limits of travel and beyond such 30 limits.

A further object of my invention is the provision of means for effecting the application of a brake at the limits of travel of a hoisting machine and combining therewith 35 a stop-motion apparatus which will exert an extra squeeze on the brake beyond such limits, and having a single electro-magnet capable of releasing the brake after such 40 extra squeeze has been exerted as well as at the ordinary limits of travel.

Other objects of the invention will appear hereinafter, the novel features and combinations of elements being set forth in the appended claims.

My invention will be more readily understood by reference to the accompanying drawing which form a part of this specifi-

cation, and in which the figure is a side elevation of an electric elevator hoist equipped with a brake constructed in accordance with 55 my invention.

The mechanism shown in the drawings includes a cable drum, 3, (the cable being omitted) is mounted on a shaft driven 60 by an electric motor, a brake, a brake-applying mechanism, and a separate mechanism 65 for automatically breaking the motor circuit when the car arrives at a predetermined point.

The cable winding drum, 3, (the cable being omitted) is mounted on a shaft driven 65 by a worm gear (not shown) inclosed by a frame or housing, 4, the lower portion of which contains oil in which the worm rotates.

On the shaft, 5, preferably between the motor and the gear housing, is fixed a brake-wheel, 7, which, when checked by the brake, stops the motor shaft, the drum, 3, and the elevator. The brake is constructed for mechanical actuation and preferably electro-magnetic release. To that end it preferably 75 comprises a pair of brake-levers, 8, provided with large friction surfaces to engage opposite sides of the face of the brake-wheel. The friction surfaces may be metallic or non-metallic; as shown, the shoes are lined with 80 strips, 9, of wood or other material which offers a high degree of friction with the brake-wheel. The brake-levers, 8, are pivoted, preferably at points distant from the ends to which the braking power is applied. 85

The lower ends of the brake-levers, 8, are pressed or drawn together by a spring or springs, 18 and 26, normally operating or tending to "set" the levers upon the brake-wheel. Except when the levers are positively disengaged from the brake-wheel they are pressed against the brake-wheel by these 90 springs and hence tend to stop the elevator. Such is the main or normal braking action. I supplement this by increasing the pull or 95 pressure of the springs at desired times. The supplementary action is brought about by auxiliary brake operating mechanism so constructed and arranged as to be operated by the last part of the movement of the 100 hoisting mechanism in either direction, i. e., at moments when the elevator car approaches the top or the bottom of the elevator shaft.

The means for applying the brake-levers to the brake-wheel preferably comprise a rockable member, means for rocking it, and pull-rods actuated thereby and connected to the brake-levers through the medium of springs. As shown, a disk, 15, on a rock-shaft, 16, actuates two rods 17, which pass through slots in the brake-levers, 8, but are not pivoted to the latter. The springs, 18, 10 are interposed between the levers, 8, and nuts, 19, on the rods, 17, for the purpose hereinbefore stated. The rockshaft, 16, is provided with an arm, 20, connected to which is a rod, 22, actuated by a cam-operated lever, 23. If the rod, 22, rises to apply the brake, the cam, 24, is arranged above the lever, 23, as shown. The cam is loosely mounted on a screw shaft, 25, and is actuated as hereinafter described. It is eccentrically formed, and its lowest portion is held normally above the cam lever roller, thereby leaving the parts in the positions shown. Even in this position of the parts, the springs, 18, exert braking pressure upon 25 the brake-levers, 8, this pressure being employed for stopping the elevator at the intermediate floors.

As an additional safeguard I provide an auxiliary or supplementary brake-applying means for exerting an extra squeeze on the brake when the elevator winding mechanism travels beyond its ordinary limits by reason of momentum or otherwise.

If desired, the springs 18 may be depended upon for the ordinary braking operation between limits of travel, each spring 18 acting on its respective brake shoe. In such cases the spring 26 may be omitted. It will be seen that the brake-applying springs 18, 40 18 are arranged to tend to draw the brake-levers together or against the surface of the brake pulley. But even when all the springs 26, 18, 18 are used their combined action is insufficient to prevent the brake-magnet from releasing the brake beyond the ordinary limits of travel after the emergency brake-applying means has operated. In some cases it is of advantage to employ the spring 26 in addition to the springs 18, 18 45 because the safety of the brake apparatus is increased. If one of the springs 18 should break, the spring 26 may be relied upon to apply the brake-shoe associated with such broken spring. If the spring 26 is omitted 50 and the springs 18, 18 relied upon for the ordinary application of the brake and one of the springs 18 should become broken, sufficient force could be transmitted through the other spring 18 by the emergency brake-applying means to apply at least one brake-shoe to the pulley to effectually stop the elevator winding mechanism before the latter traveled too far beyond its ordinary limits. It should be understood that although the 55 spring 26 may be used for applying the

brake under normal condition and that the principal functions of the springs 18, 18 may be to cushion the action of the emergency mechanism, the spring 26 may be omitted and the springs 18, 18 relied upon to apply the brake under normal conditions between the limits of travel of the elevator winding mechanism. At the ordinary limit of travel of the winding mechanism one of the stop-motion devices comes into play to 70 cut off the current from the brake-magnet; therefore the springs will apply the brake in the usual manner. If this is insufficient, however, to stop the elevator winding mechanism by reason of too much momentum or otherwise, the supplementary or auxiliary stop-motion device will afterward come into play to operate the emergency brake-applying means and transmit additional force through the cam 24, the lever 85 23, the rod 22, the arm 20, disk 15, links 17, 17 and springs 18, 18, thereby exerting an extra squeeze on the brake-shoes. After the elevator winding mechanism has been stopped by the emergency brake-applying 90 means, the springs 18, 18 may be further compressed by the energization of the brake magnet so that the brake can be released and the elevator started in the opposite direction.

It should be particularly noted that since 95 the same brake-magnet which is used between the ordinary limits can be used for also releasing the emergency brake apparatus, the operator is not required to reset the apparatus by manual manipulation at 100 the winding mechanism but may release the brake by an electric switch at a distance.

It should be understood that the right hand end of the spring 26 acts on the disk 27, which is attached to the rod 28, shown at the left, and that the spring 26 also acts on the left hand disk 27, which is attached to one or two rods shown at the right. Preferably this construction consists of two rods 28 at one side passing loosely through the 110 disk on the same side and a single rod upon the other side passing loosely through the disk at the corresponding side. The spring 26 therefore acts on both brake shoes 8, 8 to urge the same toward the brake pulley in 115 a manner well understood.

The means for retracting the brake and holding it off during travel of the elevator car, are preferably electromagnetic. An embodiment of this idea consists of a solenoid, 120 10, provided with two iron cores or plungers, which are loosely connected to the short ends of the brake-levers, 8; said cores being drawn apart when the brake-levers are set. Said levers are pivoted on lugs, 14, 125 which may be integral with the iron shell, 13, inclosing and supporting the solenoid. Said shell is held by the gear housing, 4. When the magnet, 10, is energized it pulls in its cores, which turn the brake-levers and 130

retract them from the brake-wheel, 7. The magnet has connections to the controller on the elevator car, by which means it is energized just before the motor is started.

5 My auxiliary and limits mechanism for augmenting the normal braking pressure, automatically, is driven by the elevator drive mechanism, as more fully described hereinafter. The automatic mechanism for 10 throwing the limit switch is also driven by the elevator drive mechanism and is preferably constructed as follows: The shaft of the cable drum, 3, is provided with an extension, 29, the outer portion of which is 15 screw threaded and the inner portion smooth. Fixed upon the inner portion—*i. e.*, adjacent to the housing, 4,—is a gear or pinion, 30, and loosely mounted at one side of said gear, is a gear or pinion, 31, 20 which is secured to or integral with a grooved wheel, 32, and is also secured to a double yoke, 33, which also turns freely upon the extension, or screw shaft, 29. The yoke and gear, 31, are held normally in a certain position, by means of a weight, attached to a flexible member one end of which is attached to the periphery of said grooved wheel, 32.

The loose gear or pinion, 31, meshes with a driven gear, 40, on a rotary shaft, 41, journaled in a rigidly supported housing, 42. Upon shaft, 41, is arranged a rotary limit switch, comprising preferably, a suitable number of contact segments or rings, with contact fingers or brushes arranged to make 35 and break contact and open or close circuits when the rings or segments are turned. This limit switch, designated LS as its name implies, is operated only at or near the limits of the car's travel, and its office is to slow 40 the motor, when the car approaches the top or bottom of its shaft, and then to break the motor circuit, before the car arrives at the top or bottom landing.

The rotary portion of the switch is held 45 yieldably in normal position by the gears, 31 and 40 and the weight connected to the gear 31 and yoke 33. In this position the contact lug, 46, is in contact with two of the fingers, 47. The contact fingers are held in 50 any suitable manner, for example as shown in Figs. 3 and 4, their holders being insulated from the metal rod, 49. The other contact fingers are normally upon the middle points of the segments, 44—45, and the operation of the switch is the same, in both directions, of movement, *i. e.* when the car moves either up or down.

The contact fingers, 47, of the limit switch are connected in circuits of several relay or 60 magnet operated switches, all on a controller board (not shown). Said switches may be termed respectively, a line switch, an operating switch, and a motor slowing switch.

All said switches are held closed when the 65 limit switch is at normal, or centered. The

motor slowing switch, when closed, introduces a resistance into the motor field circuit which permits maximum speed of the motor armature. When the limit switch is turned in either direction, it successively de-energizes the magnets of the above named switches, the effect being that the said motor resistance is cut out, reducing the speed of the motor; the armature circuit is then broken, and finally the solenoid, 10, is de-energized, permitting the brake to be applied.

The preferred construction is such that the circuit of the retracting magnet, is opened prior to the supplementary application of 80 the brake by the auxiliary mechanism.

The means by which the limit switch is operated may be, and are shown as, carried by the screw shaft, 29, within the yoke, 33. Two dogs, 50, are tightly clamped upon the 85 screw, 29, their distance apart being determined by the length of the elevator shaft. Each is provided with a tooth, 50'. Between them, is a traveling nut N, having two teeth, 51', and having extensions, 51'', that 90 engage ribs, 33', in the frame, 33, while permitting the nut to travel upon the screw shaft, 29, when the yoke is not being rotated. The dogs, 50, are so spaced that one or the other will engage a tooth, 51', of the nut, N, 95 when the elevator car comes within a predetermined distance from the end of its travel. As soon as this occurs, the nut will be caught and turned at the same speed as the screw, while its longitudinal motion will be arrested. By turning, it will turn the yoke, 33, wheel, 32, gears, 31 and 40, and the limit switch. The said movement of the wheel, 32, will draw up the chain and weight connected thereto. Upon the reverse movement 100 of the car, (either up or down) the weight, acting through the chain, will cause the nut, 51, to follow the dog, 50, back until the weight has descended as far as it may. At this point the weight stops the rotation of 105 the yoke, 33, hence the nut, 51, and the latter begins to move along the screw toward the opposite dog, 50.

The mechanism for automatically increasing the normal braking pressure near the 115 limits of the elevator's travel, is shown as a duplicate of that above described. On the screw shaft, 25, is mounted a yoke, 53, provided with a chain-wheel, 54, chain, 55, and a weight, 56, for holding it centered. The 120 screw shaft, 25, is provided with a gear, 57, which is turned by the gear, 30, fixed upon the upper screw-shaft, 29. The cam, 24, being integral with or secured to the chain wheel, 54, is held normally by the weight, 56, 125 in the position shown. The dogs, 58, on screw shaft, 25, are so adjusted that one of them will be engaged by, or engage, the nut, 59, when the elevator car is within a short pre-determined distance of its terminal stopping 130

points, and after the limit switch has been operated. The positive rotation of the cam, 24, by the frame, 53, forcibly moves the lever, 23, and actuates the rod, 22, rock-arm, 5, 20, disk, 15, brake-rods, 17, and the brake levers, 8, the pressure being transmitted to said levers through the medium of springs, 18. It is evident that said springs will permit the retraction of levers, 8, by the magnet, 10, when the operator starts the car on the return trip, though the rods, 17, will not be fully retracted until the cam, 24, has been returned to normal, by the weight, 56.

At every stoppage of the elevator, by the operator, the circuit through the solenoid, 10, will be interrupted, thereby releasing the brake-levers to the springs, 18, which will apply them with moderate pressure to the brake-wheels, 7. The pressure of the springs, 18, may be varied by adjusting the nuts, 19; and the brake pressure at intermediate stops may also be regulated without turning said nuts, if the connecting rod, 22, be provided with means for longitudinal adjustment, such as a turn-buckle. As the brake shoes wear away the rod may be shortened accordingly. The solenoid circuit includes, for each direction of the car, an operating magnet switch and a line magnet switch (not shown) which are closed by the manually-operated controller on the car when the elevator is started; thus the brake is released. Said magnet switches forms a part of an elevator controller which is not carried upon the car.

Supposing the car to be stopped at a point midway between the top and bottom floors, the operation is as follows: The operator starts the motor, which rotates the drum 3, 40 screw shaft, 29, and gear wheel, 30, thereon. Gear, 30, turns the lower screw shaft gear wheel, 57. At a determined point, near the limit of travel of the car, the yoke, 33, on the upper screw shaft begins to revolve, and causes the pinion, 31, to turn the limit switch gear wheel, 40, which operates the limit switch, and the latter causes the speed of the motor to be reduced. Further movement breaks the motor circuit and then opens the 50 brake magnet circuit.

When the magnet circuit is opened, the magnet, being deenergized, ceases to hold the brake arms away from the brake wheel, hence said arms are set against the wheel by the pressure of the springs 18 and 26. A further action follows immediately, that is, continued rotation of the shaft 25 causes the traveling nut 59 to engage one or the other of the nuts 58, hence the yoke 53 is rotated and carries with it the cam wheel 24, thereby further setting the brakes by drawing up the rod 22.

The initial action of the brake which occurs at the moment that the magnet is deenergized coupled with the supplementary

braking action through the medium of the yoke cam, and rod 22 is sufficient to bring the car to a stop at the desired point at all times notwithstanding variation in speed of the car or its load.

The primary action of the brake is depended upon to bring the car nearly to a stop when loaded heavily, or when moving at a high speed, and is also capable of bringing the car to a smooth even stop under light loads. I depend upon the action of the cam and the other members of the limit brake to apply the force which is necessary to stop the car, when the speed or weight of the car is such that the primary action is insufficient. In other words the limit brake goes into action whenever the slip of the brake wheel for any reason becomes excessive.

When the operator manipulates the car controller to start the car, the solenoid, 10, is energized and retracts the brake; the weights, attached to the sheave 32 and the weight 56, descend and bring the limit switch and cam, 24, respectively, to normal. The motor may be run at full speed or at any desired lower speed, at the will of the operator.

As various modifications of the invention will readily suggest themselves to one skilled in the art, I do not limit my invention to the specific form and constructions herein described.

Having thus described my invention, I claim as new and desire to secure by Letters Patent:

1. In a brake, the combination with brake shoes, of means for applying the same, and automatic means acting through the brake applying means for increasing the application of the brake shoes.

2. In a brake, the combination with brake shoes, separate springs each applying a shoe with normal pressure, means for increasing the application of the shoes through the said springs, and a single electromagnet for releasing the said shoes both when applied with normal pressure and when under extra pressure.

3. In a brake, the combination with brake shoes, of a main spring for applying said shoes, auxiliary springs each applying one of the shoes, automatically operated means for exerting an extra squeeze on the shoes through the auxiliary springs and a single electromagnet for releasing said shoes both under normal pressure and after the extra squeeze has been exerted.

4. In a brake, the combination with a pair of brake shoes and means for applying the same, of a normally stationary lever mounted on a fixed fulcrum, actuating rods pivoted at their inner ends to said lever, abutments one at the outer end of each of said rods, springs one interposed between

each abutment and a brake shoe, and means for moving said lever to effect an extra squeeze on the brake shoes.

5. In a brake, the combination with brake shoes, of two separate springs each acting to apply one of said shoes with normal pressure, a lever fulcrumed between said springs, an oscillating member connected to the lever at its fulcrum, a pair of links connected between said springs and said oscillating member, and means for actuating said lever to effect an extra squeeze on the brake shoes through said springs.

6. In a brake, the combination with brake

shoes, of means for applying the shoes, automatic means acting through the brake-applying means for increasing the application of the brake shoes, and an electromagnet for releasing said shoes after said additional force has been exerted.

In testimony whereof, I have hereunto set my hand, this 24th day of September, 1906, in the presence of two subscribing witnesses.

CLARENCE W. WHEELER.
